PAPERBOARD PRINTING PLATE AND PROC-
ESS OF MAKING SAMEJames S. Royse and Paul R. Turner, Terre Haute,
Ind., assignors to Thomson Symon Co., Terre
Haute, Ind., a corporation

Application October 28, 1935, Serial No. 46,971

12 Claims. (Cl. 101—401.1)

This invention relates to the process of forming a printing plate and the printing plate resulting from said process.

The chief object of the invention is to form a 5 printing plate of paper board character.

In the printing, for example, of billboard posting copy, the original standard sizes were 24 sheets each of which was approximately 28" by 42", although recently this entire copy for a billboard has been reduced in sheet number and increased in the size of sheet, to wit, ten sheets approximately 43½" by 60½". Thus, each sheet is of relatively large area and the material itself, used in printing plates heretofore, for printing 10 such sheets, has been a material item of cost.

The chief feature of this invention consists in the reduction of that cost without destroying the length of life of the printing plate resulting therefrom and without forming from the plate a 20 commercially unsatisfactory sheet of bill board copy.

Of course, the invention can be applied to smaller sizes, although the total savings are not as large in the aggregate.

25 Plates produced by this process have at the present time been commercially utilized in runs exceeding 1,100 impressions per plate, this being the largest commercial order upon which the invention has been utilized to date, the same producing one sheet of copy for approximately 1,000 billboards, the extra 100 being the customary overrun to compensate for spoilage in the running and board application of the posters.

The process portion of the invention consists 35 in the utilization of a suitable base of billboard sheet size or the desired size and to the same is secured a composite paper board structure resulting in a composite plate for subsequent printing when the impression is formed therein.

40 It has been determined that best results, and by the same is meant the finished sheet of copy for pasting on the billboard, is obtained when the paper board portion of the plate is resiliently and adhesively secured to the supporting base. The 45 paper board portion of the plate includes two types of paper board, one fairly hard and the other still harder and of a smoother and higher calendered finish, the two being adhesively secured together preferably with a resilient union.

Also, since the paper board portion of the plate is of multi-layer character, preferably the first two layers are secured together throughout their entire adjacent faces. When but two layers are 55 utilized, substantially all of the non-printing

areas of the paper board printing plate are removed from the supporting base.

It has also been determined that to obtain a paper printing surface which does not mar or become rapidly unprintable after few impressions 5 have been taken therefrom, it is highly desirable to seal the minute pores in the exposed ink-receiving face of the paper board—in other words, to transform this printing surface from possibly ink absorbing character, although very slight, to 10 almost non-absorbing character.

This transformation is frequently necessary and particularly so for large or long runs because printing ink is tacky and if the plate printing surface is but slightly porous, the ink applied thereto 15 will gradually through repeated suction operation, result in marring of the plate printing surface so that the resultant copy when printed, will not have that uniformity and depth of color and 20 sharpness of outline which is characteristic of metal printing plate production. This sealing bonds the surface fibres together so the surface resists suction deformation.

The present invention, however, produces a 25 plate which will produce copy comparable to that produced from a metal printing plate. It, of course, is understood that metal printing plates, particularly of large size hereinbefore specified, are composed of a suitable multi-ply wood base, to which is secured the metal face, usually of 30 sheet zinc, upon which is formed in relief the printing portions and the comparative cost between paper board and the metal, resulting in a marked saving will be self evident.

A thin solution of white transfer lacquer not 35 only provides the surface seal or fibre bond for the plate printing surface but provides a surface which is more or less sensitive to the lead (graphite and the like) of an ordinary lead pencil in that the original of the copy may be laid out 40 on a sheet and then by rubbing with pressure on the copy applied to the lacquered face of the plate there results the transfer of sufficient lead from the copy to the plate printing face to permit the workmen to follow the transferred copy lines and 45 cut through the two layers of paper board to remove from the plate the portions which are to be left blank corresponding to the portions which are not to be printed by the plate on the final paper copy.

It has been found that in order to secure the best results in the final copy and since copy substantially identical to that obtained from metal plates is desired, due to the lack of rigidity and 50 toughness of a paper printing surface as dis- 55

tinguished from a metal printing surface, some cushioning or yielding effect should be provided and preferably this is obtained in the adhesive connection between the layers of paper board plate structure and between the composite paper board plate structure and the multi-ply base structure. This type of connection also compensates for any irregularities in the thickness of the several pieces of paper board utilized.

Usually, the resultant board is type high for mounting upon the bed of a cylinder press, such as a "6-0" flat bed cylinder Miehle press.

The formation of the printing impression on the plate is made by sharp tools cutting through the multi-ply paper board stock to the multi-ply wood base and following removal of the portions so cut out, the printing surface remaining has removed therefrom the surplus lacquer or at least that portion which is not utilized in sealing the minute pores and bonding the surface fibres together and also if, as and when desired, all cement on the wood board base exposed by the removal of the paper board portions may be removed. The impression intended, therefore, stands out in relief and will print when inked, copy substantially of the same character as printed by a metal plate.

No claim, however, is made that the life of a paper board plate of this character is equal to that of a metal printing plate of equal printing character but it is asserted that for fairly large runs, a paper board printing plate is equally as satisfactory as a metal printing plate and much cheaper to produce.

Heretofore in the industry, in order to reduce the cost of these large metal plates, a rubber mat surface instead of a metal mat surface has been utilized and it has been determined that a paper board plate of the present invention has a length of life sufficient for the usual requirements for which a rubber mat is utilized. In one size, the present cost of a rubber mat plate is about \$8.50, whereas, the present cost of the present invention (paper board printing plate) is only \$1.25 or there results a saving in plate fabrication of \$7.25 per plate. If these comparative costs apply to the largest size plates mentioned for the ten plates necessary to produce a one-color complete copy for a billboard, there is a saving in plate cost of \$72.50, and as will be well understood by those engaged in the printing industry, there will be an additional saving in plate cost in the same proportion as to the number of plates required for the reproduction.

Having now described in some detail the process of preparing a printing paper board plate, reference will now be had to the plate per se and in describing the same, further reference will be had to the process of preparing or forming it.

The full nature of the invention will be understood from the accompanying drawing and the following description and claims:—

In the drawing, Fig. 1 is a plan view of a printing paper board plate, the left hand portion having the printing face thereon in relief formation and the right hand portion illustrating the paper printing plate preliminary to the formation of the printing impression therein.

Fig. 2 is an enlarged sectional view taken on line 2—2 of Fig. 1, and in the direction of the arrows and substantially of a plate in the stage prior to final completion.

Fig. 3 is a similar sectional view taken on line

3—3 of Fig. 1 and illustrates the printing plate in its final or completed form.

In the drawing, 10 indicates a suitable base, herein illustrated as of five ply wood stock. The numeral 11 indicates a layer of adhesive which secures to the base the main body portion of the stock 12 in turn secured on its opposite face by the layer of adhesive 13 to the liner 14.

It has been determined that a suitable liner or facing sheet is one that may be designated as .020 red press board and that the main body of the paper portion of the printing plate may be what is known as 80 point news board. The press board is what may also be termed a relatively heavy fibre board having a very hard surface. It is almost the thickness of card board. The news board is slightly less than $\frac{1}{8}$ " in thickness.

The preferred method of assembling the plate structure is to coat one side of the 80 point news board with rubber cement and at the same time coat one side of the .020 red press board. These two coated surfaces are then allowed to dry naturally or may be dried more rapidly by forced drying. The cement coated sides of these two boards are then pressed together and this forms what may be termed the "surface plate" and corresponds to the metal "mat" on the plate in the printing industry.

The base 10 is approximately $\frac{3}{4}$ " thick and the unlined or unsurfaced face of the surface plate and one face of the base,—each is similarly coated with rubber cement,—is permitted to dry until the respective coated surfaces become tacky, and then are secured together by a pressure arrangement. In the drawing, the cement layers 11 and 13 are intentionally represented as slightly thicker compared with reference to the liner or facing sheet 14, the paper body 12 and the base 10.

After the entire plate structure has been built up, as aforesaid, the impressions, as previously set forth, may be formed in relief thereon by cutting away the liner and body portion down to the base 10. This will form a printing plate of satisfactory printing capacity having reference to a fairly convenient number of printing impressions or printing workmanship equivalent to a metal plate. However, for a relatively large number of impressions and to insure perfect printing, it is preferred to seal or bond the surface of the liner or facing sheet. There is, therefore, applied to the exposed face of the liner a thin solution of lacquer. This seals all imperfections in the exposed printing surface of the liner or surface sheet and bonds the surface fibres together. This lacquer may be sprayed or brushed thereon. Greater uniformity, however, is obtained by the spraying application.

To facilitate the formation of the printing impression on the printing plate, instead of using a colorless lacquer, there is utilized a white lacquer. This is known as white transfer lacquer and it is more or less sensitive to an ordinary lead pencil. The transfer of the desired design to the printing plate is made by merely turning the design in its normal relation, which has been made by pencil on ordinary litho-paper, face down on to the lacquer coating and then transferring the lead lines or a part of the lead of the lines on the litho-paper to the printing plate and particularly to the white lacquer surface thereof by "rubbing". This "rubbing" leaves a sufficient representation of the desired design in reversed relation on the white lacquer surface.

Any omissions in the design may be filled in by pencil, if necessary, and then the plate is cut by hand or by tools, as desired, and usually the cuts are carried through to the base 10 and preferably 5 the cuts are inclined to the plane of the base as shown. After cutting through to the plane of the base, the parts of the printing plate which are not to print in the final plate, are removed from the base which thus leaves the intended impression 10 or printing portion of the plate standing out in relief from the base 10.

After the plate has been completely cut, all surplus lacquer on the liner face or facing sheet is suitably removed by the use of any desired lacquer 15 solvent. Of course, the solvent does not remove that portion of the lacquer which seals the imperfections or adheres to the surface fibres for bonding thereof. It merely removes the excess surface coating. It might be stated these imperfections are extremely minute in character and usually are not visible to the eye, although they may in the long run due to ink suction action, if not eliminated as set forth, result in poor printing in the latter portion of the longer run. The 20 cement which adheres to the base following the removal of the cutout portions of the paper board portion of the printing plate is then suitably removed in any desired manner, leaving the exposed portion of the base 10 clear or relatively 25 free from cement.

It may be questioned as to why a single thickness of paper board might not be utilized in the same manner that a single sheet of rubber or metal is utilized and in answering the same, it is 30 pointed out that a single thickness of board, if of the news board type, does not have a hard enough surface and if of the press board type, is possibly too hard. Likewise, the addition of a cushion adhesive connection between the two compensates 35 for irregularities therebetween.

News board stock as an exposed printing face, is not satisfactory because of the tackiness of the ink and a rough surface in the board printing face results after a relatively few impressions due 40 to such ink suction, which in turn results in poor printing. It has been tried and the most satisfactory impressions have been only about fifty in number.

Also, it may be stated that other types of board, 50 heavier and lighter than 80 point news board, have been utilized with better results than just plain news board. However, it has been found that press board which has a high calendered finish and is relatively hard and built up to approximately 80 point, is the most satisfactory for 55 use in the formation of a printing paper plate that will produce printing substantially equal in character to that obtained from metal plates.

It might also be stated the foregoing description 60 has been directed to a printing plate, that is, what is known as type high, in total thickness, although for purposes where such a height is not desired, the thickness of the plate may be varied accordingly.

It might also be added that the utilization of 65 an imperfection preventing sealing medium prevents peeling of the liner for the liner face or surface will, after a considerable run, start to peel at its weakest point—the imperfection—due to the suction and tackiness of the ink in its 70 repeated application to the plate and its repeated transfer to the paper to be printed.

In the drawing, 15 indicates the white transfer lacquer and the dot 16 in Fig. 2 represents the 75 pencil transfer legending that has been rubbed

on to the lacquer from the litho-sheet bearing the original design. 17 indicates the tapered or inclined cut and the surface 18 indicates the sealed printing surface of the printing paper plate.

The use of the litho-paper with the lead impression thereon and the subsequent transfer by rubbing of the lead lines upon the lacquer, it will be obvious, results in a mere surface addition and all of the corrections may be made previously in 10 the copy on the lithopaper and no corrections will be subsequently required on the plate. Also, instead of tracing through a copy made in reverse form, the copy is made in its original form and reversely applied. A better visualization of the 15 completed copy may thus be obtained by this method. This method furthermore has the additional and more important advantage that the printing surface is not mutilated in the copy transferring step so that only the cutting tool need 20 engage this surface and form the sharply defined edge, leaving in relief the printing surface without imperfections or irregularities in either the surface or the edge immediately adjacent thereto, which might result if a stylus were used.

While the invention has been described in great detail in the foregoing description, the same is to be considered as illustrative, not restrictive in character, and as has been pointed out hereinbefore, various modifications of the invention, 30 both in the product and the article, have been set forth, and these as well as others which will readily suggest themselves to persons skilled in this art, are considered to be within the broad scope of this invention, reference being had to the appended claims.

The invention claimed is:—

1. A printing plate including a supporting base and a printing body, the latter comprising a relatively dense liner of paper board stock, and of but 40 slight thickness, and a relatively thicker main portion of paper board stock secured at opposite faces to the liner and the base.

2. A printing plate including a supporting base and a printing body, the latter comprising a relatively dense liner of paper board stock, and of but 45 slight thickness, a relatively thicker main portion of paper board stock, and an elastic adhesive connection between the liner and main portion and main portion and base.

3. A device as defined by claim 1, characterized by the liner being substantially .020 red press board.

4. A device as defined by claim 1, characterized by the main portion being approximately 80 point 55 news board.

5. A device as defined by claim 2, characterized by each elastic adhesive connection consisting of rubber cement.

6. A device as defined by claim 1, characterized by the addition of a filler to the exposed face of the liner.

7. A device as defined by claim 1, characterized by the addition of a filler to the exposed face 65 of the liner, said filler comprising a thin solution of white transfer lacquer permitting pencil copy transference and the major portion of which is readily removed following plate cutting.

8. The process of preparing a printing plate 70 from paper board, including resiliently securing a facing sheet to a paper board body, resiliently securing the body to a supporting base, sealing the imperfection in and bonding the exposed fibrous surface of the sheet, and cutting in relief the 75

desired impression in both sheet and body preliminary to forming the printing impression.

9. The process of preparing a printing plate from paper board, including resiliently securing a paper board facing sheet to a paper board body, resiliently securing the body to a supporting base, sealing the imperfection in and bonding the exposed fibrous surface of the facing sheet with a copy-receiving medium, and applying the desired copy thereto preliminary to forming the printing impression therein.

10. The process of preparing a printing plate from paper board, including resiliently securing a facing sheet to a paper board body, resiliently securing the body to a supporting base, applying to the exposed face of the facing sheet a copy receiving-medium, applying the desired copy thereto preliminary to forming the printing impression therein, and removing all surplus medium subsequent to impression formation and preliminary to printing therefrom.

11. The process of preparing a printing plate

from paper board, including resiliently securing a paper board facing sheet to a paper board body, resiliently securing the body to a supporting base, sealing the imperfections in and bonding the exposed fibrous surface of the facing sheet with a copy-receiving medium, applying the desired copy thereto preliminary to forming the printing impression therein, and removing all surplus medium subsequent to impression formation and preliminary to printing therefrom.

12. The process of preparing a printing plate of paper, including forming a composite paper board plate structure on a supporting base, the structure including an outer facing sheet of paper board and an intermediate body of paper board, sealing the imperfections in and bonding the fibrous ink-receiving surface of the sheet, and cutting the printing impression therein prior to printing therefrom, the printing impression being in relief.
